CLAIM

The ornamental design for a disposable hand held verifier, as shown and described.

DESCRIPTION

FIG. 1 is a perspective view of a disposable hand held verifier showing my new design;

FIG. 2 is a front elevational view thereof;

FIG. 3 is a back elevational view thereof;

FIG. 4 is a right side elevational view thereof;

FIG. 5 is a top elevational view thereof; and,

FIG. 6 is a bottom elevational view thereof.

The broken line showing of the decorative human forms in FIGS. 1 and 2 is for illustrative purposes only and forms no part of the claimed design.
